By Cadmon & Co.
Attorney

UNITED STATES PATENT OFFICE.

JOEL TERRELL, OF LOS ANGELES, CALIFORNIA.

FINGERPRINT.

Application filed August 2, 1922. Serial No. 579,184.

To all whom it may concern:

Be it known that I, JOEL TERRELL, a citizen of the United States, residing at Los Angeles, in the county of Los Angeles and 5 State of California, have invented a new and useful Fingerprint, of which the following is a specification.

The present invention relates to a novel method of preventing fraud by the use of 10 finger prints, or the combination of finger prints.

The object of the invention is to provide novel means for proving the ownership of a card or the like, by the combination of 15 finger prints overlapping each other so that both finger prints would be marred in the event that a person endeavored to erase or change the original finger prints.

The figure illustrates a motor vehicle operator's license, the overlapping finger prints being shown thereon.

Referring to the drawing in detail, the reference character 5 designates the license card issued to prove that the person holding the card is entitled to operate a motor 25 vehicle, within a stated territory.

The card is supplied with the person's name to whom the same is issued, and one portion of the card is ruled to provide a 30 space 6 for the reception of the finger prints of the person issuing the card, as well as the person's finger prints to whom the card is issued.

As shown, the finger prints are overlapped, the reference characters 7 indicating 35 as for example, the finger print of the person issuing the card, while the reference character 8 designates the finger prints of the person to whom the card is issued, so that should the card fall into the hands of some 40 person not entitled to use the same, the person could not by erasing thumb print 8, place his finger print thereon without obliterating the finger print of the person who issued the card, to the end that the card 45 would show that the finger print had been tampered with.

While I have shown and described the invention as used on license cards, it is to be understood that the method of identification 50 may be employed on various types of identification cards or documents.

It might be further stated that the finger prints may be made with varied colored inks to render it more difficult for persons 55 to change the finger prints.

Having thus described the invention, what is claimed as new is:

A method of identification including providing a card, and placing finger prints 60 thereon, one finger print overlapping the other finger print.

In testimony that I claim the foregoing as my own, I have hereto affixed my signature.

JOEL TERRELL.
